(57) **CLAIM**

We claim the ornamental design for a radio transceiver, as shown.

DESCRIPTION

FIG. 1 is a left view of a radio transceiver;

FIG. 2 is a front view of the radio transceiver;

FIG. 3 is a top view of the radio transceiver;

FIG. 4 is a bottom view of the radio transceiver;

FIG. 5 is a right view of the radio transceiver; and,

FIG. 6 is a back view of the radio transceiver.
